[57] CLAIM

[21] Appl. No.: 273,503

The ornamental design for a combined key ring and
container, as shown and described.

DESCRIPTION

FIG. 1 is a front elevational view of a combined key
ring and container showing my new design in partial
cross-section;

FIG. 2 is a rear elevational view shown in the retracted
position;

FIG. 3 is a right side elevational view;

FIG. 4 is a left side elevational view;

FIG. 5 is a bottom plan view of the key ring;

FIG. 6 is a top plan view of the key ring.
